UNITED STATES PATENT OFFICE.

WILLIAM B. STEWARTSON, OF PITTSBURG, PENNSYLVANIA.

DESIGN FOR A SHADE-HOLDER.

SPECIFICATION forming part of Design No. 14,638, dated February 5, 1884.

Application filed November 22, 1883. Term of patent 14 years.

To all whom it may concern:

Be it known that I, WILLIAM B. STEWARTSON, a citizen of the United States, residing at Pittsburg, in the county of Allegheny and State of Pennsylvania, have invented and produced a new and original Design for Illuminators or Shade-Holders, of which the following is a specification, reference being had to the accompanying drawings, forming a part thereof.

My design consists of an illuminator or shade-holder having a flaring body, a vertical edge, and a heel of the form of an unbroken parallelogram with rounded corners and slightly curved ends, the essential feature of the design being the heel or base of this shape.

Figure 1 represents an inverted view of my newly-designed illuminator or shade-holder, looking at the lower end of the heel; and Fig. 2, a vertical sectional view of the same.

The letter A indicates the flaring body of my illuminator or shade-holder, the general contour of which is substantially of the form of a frustum of cone inverted, its upper edge terminating vertically in a seat, B. The lower end of the body is provided with an opening, in form agreeing with that of an unbroken

parallelogram, save that the corners are rounded and the ends slightly curved. Extending from this portion of the illuminator is a "heel" 30 or base, C, the same being of the form just described—that is, of an unbroken parallelogram, the corners being rounded and the ends slightly curved.

I claim—

1. The design for an illuminator or lamp-shade holder herein shown and described, the same consisting of a flaring body terminating vertically at the top, having an opening at the bottom of the form of an unbroken parallelogram rounded at the corners and slightly curved at both ends, and a base or heel extending therefrom and agreeing in configuration with the said opening.

2. The design for the heel or base of an illuminator or lamp-shade holder of the form of an unbroken parallelogram having its corners rounded and its ends slightly curved.

WILLIAM B. STEWARTSON.
